UNITED STATES PATENT OFFICE.

BENJAMIN F. LEE, OF SCHOOLFIELD, VIRGINIA.

SOUND-TRANSMITTER.

1,176,577.

Specification of Letters Patent. Patented Mar. 21, 1916.

Application filed February 9, 1915. Serial No. 7,078.

To all whom it may concern:

Be it known that I, BENJAMIN F. LEE, a citizen of the United States of America, residing at Schoolfield, in the county of Pennsylvania and State of Virginia, have invented new and useful Improvements in Sound-Transmitters, of which the following is a specification.

This invention relates to improvements in sound transmitting devices and has particular application to a telephone transmitter.

As is well known, it is essential that the telephone transmitter should cause the transmission of the sound waves to the receiving end of the line in such manner that the original sounds will be reproduced clearly and distinctly. In the present form of transmitter the reproduced sound waves do not possess the requisite clearness under all conditions, as, for instance, when the original sound waves are produced by the speaker talking in a loud tone. This defect in the transmitter is due to the fact that the sound waves, when leaving the speaker's mouth, impinge against the diaphragm and are reflected back into the speaker's face and then again reflected toward the diaphragm and so on until all the energy of the waves has been dissipated. This objectionable characteristic is partially overcome by constructing the mouth piece with a perforated bottom disposed over the diaphragm and spaced apart therefrom, such perforated bottom tending to break up the sound waves reflected from the diaphragm;

but, a little consideration will reveal the fact that this perforated bottom also prevents a portion of the sound waves from reaching the diaphragm and hence prevents the undulations of the electric current being commensurate with the original sound waves. Consequently, the sound waves reproduced by the receiver are not equal to the original sound waves, as a portion of the latter have been prevented from impinging against the sound transmitting diaphragm. Therefore, in carrying out the present invention, it is my purpose to provide a sound transmitting diaphragm which

will be constructed in such manner that the sound waves will be reflected therefrom at an angle to the original path of the waves so that the reflected waves will not interfere with the incoming waves and will not vi-

brate back and forth between the diaphragm and the source of the waves.

A further object of my invention is to construct a sound transmitting diaphragm for telephone transmitters so that the usual perforated bottom of the mouth piece may be dispensed with and whereby the sound waves will be reflected from the diaphragm at an angle to the incoming path of the waves and such reflected waves absorbed, thereby increasing the efficiency of the transmitter and enabling the original sound to be reproduced at the receiving end of the line clearly and distinctly.

With the above and other objects in view, the invention consists in the construction, combination and arrangement of parts hereinafter set forth in and falling within the scope of the claims.

In the accompanying drawing: Figure 1 is a sectional view through the mouth piece and diaphragm of a telephone transmitter constructed in accordance with the present invention. Fig. 2 is a similar view taken at right angles to Fig. 1.

Although I have shown and described my invention as applied to a telephone transmitter, I wish it to be understood that the invention, in its useful application, is not limited to this particular purpose, as the same may be employed in connection with other sound transmitters.

Referring now to the drawing in detail, 1 designates a diaphragm constructed of any suitable material and capable of vibration under the action of sound waves and 2 indicates a cup containing carbon granules connected in an electric circuit and having connections with the diaphragm 1 at the central portion thereof so that as the diaphragm is vibrated under the action of the sound waves, an undulatory current will be produced in the transmitting circuit to reproduce the sounds at the receiving end of the line, as is well known.

3 designates a mouth piece constructed of hard rubber or other approved material and having a small open end 4 and a relatively large open end 5. Suitably connected with the small end 4 of the mouth piece 3 and disposed concentrically thereof is an annular plate 6 diverging outwardly from the adjacent end of the mouth piece and having the outer edge thereof in engagement

with the marginal edge of the sound transmitting diaphragm 1 and secured to the body of the transmitter in the usual manner, the outer edge of the plate 6 and the body 5 of the transmitter clamping the peripheral edge of the diaphragm 1 to support the latter so that the same may vibrate.

In accordance with my present invention, a cone-shaped block 7 or analogous element 10 is secured to the outer face of the diaphragm 1 approximately centrally thereof and has the apex projecting toward the mouth piece. This block 7 is of a diameter at its base approximately equal to the diameter of the 15 mouth piece at the small end thereof so that the incoming sound waves impinge against the side of the cone and be reflected therefrom at an angle to the incoming waves. The inner face of the annular plate 20 6 is lined with felt or similar material 8 adapted to absorb the sound waves reflected from the side of the cone.

In practice, the sound strikes the side of the cone-shaped block 7, as indicated by the 25 arrows in Fig. 1, and is reflected against the inner face of the plate 6 and as the latter is lined with sound absorbing material, the reflecting sound waves are taken up and prevented from again impinging against 30 the diaphragm, thereby eliminating confusion of the sound waves.

While I have herein shown and described the preferred form of my invention by way of illustration, I wish it to be understood 35 that I do not limit or confine myself to the precise details of construction herein described and delineated, as modification and variation may be made within the scope of the claims without departing from the spirit 40 of the invention.

I claim:

1. In a telephone transmitter, the combination with a mouth piece, of an annular plate secured to the small end of the mouth 45 piece, a sound transmitting diaphragm secured to said plate at the outer edge thereof, means carried by said diaphragm centrally thereof to reflect the sound waves from the

diaphragm at an angle to the incoming waves, and means carried by said plate for absorbing the reflected sound waves.

2. In a telephone transmitter, the combination with a mouth piece, of an annular plate secured to the small end of the mouth piece, a sound transmitting diaphragm secured to said plate at the outer edge thereof, means carried by said diaphragm centrally thereof to reflect the sound waves from the diaphragm at an angle to the incoming waves, and a felt lining for said plate adapted to absorb the reflected sound waves.

3. In a telephone transmitter, the combination with a mouth piece, of an annular plate secured to the small end of said mouth piece and diverging outwardly therefrom, a diaphragm capable of vibration under the action of sound waves and secured to said plate at the outer edge thereof, and a cone-shaped block secured at its base to said diaphragm approximately centrally thereof and of a diameter equal to that of the small end of said mouth piece whereby the incoming sound waves will be reflected at an outward angle to the original path of said waves.

4. In a telephone transmitter, the combination with a mouth piece, of an annular plate secured to the small end of said mouth piece and diverging outwardly therefrom, a diaphragm capable of vibration under the 80 action of sound waves and secured to said plate at the outer edge thereof, a cone-shaped block secured to said diaphragm approximately centrally thereof and of a diameter equal to that of the small end of said 85 mouth piece whereby the incoming sound waves will be reflected at an angle to the original path of said waves, and means carried by the inner surface of said plate to absorb the reflected sound waves.

In testimony whereof I affix my signature in presence of two witnesses.

BENJAMIN F. LEE.
